UNITED STATES PATENT OFFICE.

THOMAS S. PUKEURUD, OF WILKINSBURG, PENNSYLVANIA, ASSIGNOR TO WESTINGHOUSE ELECTRIC AND MANUFACTURING COMPANY, A CORPORATION OF PENNSYLVANIA.

CONTROLLER.

1,357,249.

Specification of Letters Patent. Patented Nov. 2, 1920.

Application filed October 9, 1915. Serial No. 54,968.

To all whom it may concern:

Be it known that I, THOMAS S. PUKEURUD, a citizen of the United States, and a resident of Wilkinsburg, in the county of Allegheny and State of Pennsylvania, have invented a new and useful Improvement in Controllers, of which the following is a specification.

My invention relates to controllers for electric motors and particularly to controllers embodying a rotatable element and mechanism for returning it to an inoperative position.

My invention has for its object to provide a controller that is simple in construction and efficient in operation and is arranged to be automatically returned to its inoperative position during a portion of its range of movement and to remain in the position to which it is actuated during a second portion of its range of movement.

A controller constructed in accordance with my invention is adapted for use in connection with electric motors having starting resistors that are gradually shunted and having, also, means for varying the operating speeds of the motors after the starting resistors have been entirely removed from circuit. In such arrangements, it is essential that the controller be always operated through each of the several starting positions in starting the motor. Otherwise, the motor may receive an excessive current as, for example, in case a circuit breaker is closed while the controller is in an intermediate starting position. It is desirable, however, that the controller be arranged to remain in the running position in which it may be placed in order that the operator need not maintain physical force upon it during the normal operation of the motor.

In accordance with the above considerations, the controller is so arranged that it is biased to its inoperative position from each of the starting positions but is stable in each of its running positions. A single spring operates through a cam mechanism to return the controller handle to its "off" position from the starting positions and also actuates an accentuating device for retaining the handle in either of the operating positions. The spring operates, also, as a buffer to yieldingly bring the controller to rest

when it is returned to its inoperative position.

The details of my invention will be described in connection with the accompanying drawings in which Figure 1 is a view, partially in plan and partially in section, of a controller constructed in accordance with my invention. Fig. 2 is a view, partially in elevation and partially in section, of a portion of the mechanism of Fig. 1. Figs. 3, 4, 5 and 6 are views similar to Fig. 1, showing the relation of the parts of the return mechanism when the controller is in various positions.

Referring particularly to Figs. 1 and 2, a controller 1 of the drum type comprises a casing 2 having a cover member 3 that is rigidly secured to vertically extending rods 4 and 5. A rotatable shaft 6, which carries the movable contact members 7 of the switching mechanism, only a part of which is shown, is provided, at its upper end, with the usual handle 8.

The return mechanism for the rotatable parts of the controller comprises a member 9 that is rigidly secured to the shaft 6. The member 9 has a curved cam surface 10 upon one of its edges and is provided, upon another edge, with a series of notches or recesses 11. The member 9 has a projecting portion 12 integral with it for a purpose later to be described. A roller 14 is rotatably mounted upon the upper side of the member 9.

A member 16, which is pivotally mounted upon the rod 5, carries a roller 17 which contacts with the cam surface 10 or the projection 12, according to the relative positions of the members 9 and 16. The member 16 is provided with a curved projecting arm 18 having a cam surface 19 at its outer extremity for engaging the roller 14. A spring 20 yieldingly retains the member 16 in its position illustrated in Fig. 1 to hold the member 9 and its connected parts in the positions shown.

It may be assumed that the various parts are in their respective positions illustrated in Figs. 1, 2 and 3. The controller handle is in its "off" position. When the handle 8 is moved in a clockwise direction, as viewed in Fig. 3, the roller 14, which is in engagement with the cam surface 19 of the project-

ing member 18, actuates the members 16 about its pivot to place the spring 20 under tension. When the handle is in the first starting position, the various parts have assumed the relative positions illustrated in Fig. 4.

When the handle reaches the third starting position, as illustrated in Fig. 5, the member 18 has passed out of engagement 10 with the roller 14, and the roller 17 is in engagement with the cam surface 10. The member 16 has been actuated further in a clockwise direction to store energy in the spring 20. It will be evident that, if the handle be released in either of the three starting positions, the spring 20 will operate, through the roller 17 and the cam surface 10 or the projecting member 18 and the roller 14 to return the handle to its "off" 20 position.

Further rotation of the controller handle brings the several parts into their respective positions, as illustrated in Fig. 6. In this position of the controller, which is the first running position, the roller 17 engages 25 one of the notches 11 to constitute an accentuating device for retaining the controller handle and its connected parts in such position until the handle is again actuated by the operator. It will be noted that, in the running position of the controller, the spring 20 and the member 16 no longer tend to return the controller to its "off" position. The relations of the several parts in the succeeding running positions of the controller differ in no material respect from those of the position illustrated in Fig. 6, except that 30 the roller 17 occupies the notch corresponding to the position of the controller.

40 To return the controller to its "off" position, it is only necessary to actuate the controller handle in a counter-clockwise direction until it occupies approximately the position shown in Fig. 5. The spring 20 then operates, through the roller 17 and 45 cam surface 10, to continue the movement of the controller drum until the projecting arm 18 engages the roller 14. The engagement of the latter parts then tends to actuate the drum to its "off" position, as illustrated in Figs. 1 and 3. In order to insure that the drum will come to rest in its proper position, the projection 12 is arranged to engage the roller 17, and the spring 20 is 55 placed under tension if the inertia of the rotating parts tends to carry them beyond the "off" position.

It will be noted that I have provided a 60 device of simple construction in which the operating mechanism is so arranged that, when the controller handle is released by the operator, it will be returned to its "off" position during a portion of its range of travel. During another portion of its range 65 of travel, the mechanism will be yieldingly

retained in the position in which it may be placed when the handle is released by the operator. A single spring operates to effect the return of the controller drum, to yieldingly retain it in either of its operative 70 positions and to act as a buffer to yieldingly bring the parts to rest in their proper positions.

While I have shown and described my invention as employed in connection with a 75 drum controller having starting and running positions, it will be obvious that such use is illustrative only and that it may be applied to any mechanism embodying a rotatable element having a definite position 80 to which it may be desirable to return the rotatable element when it has been actuated therefrom. It is immaterial, also, whether controllers constructed in accordance with my invention are employed in connection 85 with direct current motors or alternating-current motors.

I claim as my invention:

1. In a controller, the combination with a shaft, and a member connected thereto 90 having a cam surface and a series of notches, of a spring-pressed member for successively engaging said cam surface to bias said shaft to an inoperative position and engaging said notches to retain said shaft in its operative 95 positions.

2. In a controller, the combination with a shaft rotatable in opposite directions between its normal and operative positions and a member connected thereto having a 100 cam surface and a series of notches corresponding to operative positions of said shaft, of a spring-controlled member for successively engaging said cam surface to bias said shaft to its normal position and engaging said notches to retain said shaft in the corresponding operative positions. 105

3. In a controller, the combination with a movable member having a plurality of successive positions, of means comprising a 110 unitary cam mechanism and an accentuating device for returning said member to an inoperative position from certain of said positions, retaining said member in other of said positions, and yieldingly permitting the 115 movement of said member in opposite directions from said last-named positions.

4. In a controller, the combination with a movable member having a plurality of successive positions, of means comprising a 120 unitary cam mechanism and an accentuating device for returning said member to an inoperative position from certain of said positions and for yieldingly retaining said member in other of said positions, and a 125 single spring for actuating said mechanism and said device and for yieldingly bringing said member to rest in its inoperative position.

5. In a controller, the combination with a 130

shaft, and a member connected thereto having a cam surface, a series of radially-extending notches and a projecting member, of a spring-pressed member which operates, 5 upon the rotation of said shaft, to successively engage said projecting member and said cam surface to bias said shaft to its normal position and engage said notches to 10 yieldingly retain said shaft in an operative position.

6. In a controller, the combination with a movable member having an operative position and an inoperative position, of resilient means for actuating said member to 15 said inoperative position and retaining said member in said operative position, said means serving as a buffer during said actuation to said inoperative position.

7. In a controller, the combination with 20 a movable member having a starting position and a running position, of means for returning said member to an inoperative position when it occupies said starting position, and a spring for actuating said means 25 and serving as a buffer during said return to said inoperative position.

8. In a controller, the combination with a movable member having a cam surface and a recess, of a member having means for 30 engaging said cam surface to actuate said movable member to an inoperative position and for engaging said recess to yieldingly retain said movable member in an operative position.

35 9. In a controller, the combination with

a movable member having a plurality of starting positions and a running position, of a member having a plurality of means for engaging said first member in each of said starting positions, and means for returning 40 said member to an inoperative position when it occupies any of said starting positions.

10. In a controller, the combination with a movable member having a recess and 45 adapted to occupy a starting position and a running position, of a member having a curved projecting arm for engaging said movable member in the starting position to return said movable member to an inoperative 50 position, and having means for engaging said recess to retain said movable member in said running position.

11. In a controller, the combination with a shaft, and a member connected thereto 55 having a cam surface, a series of radially-extending notches and a projecting member, of a spring-pressed member having an arm and a projection, said arm being adapted to engage said projecting member to bias said 60 shaft to its normal position, and said projection being adapted to engage said cam surface to bias said shaft to its normal position and to engage said notches to yieldingly retain said shaft in an operative posi- 65 tion.

In testimony whereof, I have hereunto subscribed my name this 24th day of Sept., 1915.

THOMAS S. PUKERUD.
